UNITED STATES PATENT OFFICE.

WILLIAM H. H. STEVENSON AND JOHN SOLTER, OF BALTIMORE, MARYLAND,
ASSIGNORS TO STEVENSON & PLUNKETT, OF SAME PLACE.

CUTTING AND PUNCHING PRESS.

SPECIFICATION forming part of Letters Patent No. 244,945, dated July 26, 1881.

Application filed April 7, 1881. (No model.)

To all whom it may concern:

Be it known that we, WILLIAM H. H. STEVENSON and JOHN SOLTER, of Baltimore, and State of Maryland, have invented a new 5 and useful Improvement in Cutting and Punching Presses; and we do hereby declare that the following is a full, clear, and exact description of the same.

Our invention is an improvement upon machines for cutting, pressing, drawing, or punching metal plate of that class in which the reciprocating head is operated by a lever, and is connected generally to a treadle.

The principal object of our invention is to 15 secure adjustability in the sliding head or plunger which carries the upper die or punch.

It also has for its object to furnish inexpensive and conveniently-operating adjustable connections and stops for the operating-levers 20 by which the sliding head is moved.

In the drawings, Figure 1 shows a side elevation of the press. Fig. 2 shows a front view of the adjustable plunger detached.

In these drawings, Fig. 1 shows an ordinary 25 form of machine in its general construction, which general construction, therefore, need not be particularly described.

The first part of our invention relates particularly to the construction of the plunger A, 30 which carries the upper die or punch. Heretofore this head or plunger has been made of one piece, and could be moved toward the lower or fixed die only by means of the lever by which it was operated. This improved part 35 of the machine is shown more clearly in Fig. 2.

In this figure the main body of the plunger is represented at A. It may be cast in one piece, and externally is of the ordinary shape, being provided with flanges, preferably of V shape 40 in cross-section, by means of which it is accurately held in guides which permit free vertical movement. This plunger is chambered, as shown at a a, the chamber extending from front to rear. Within this chamber is fitted a yoke, 45 B, fitting accurately, but loosely, at the sides, but made shorter than the chamber of the plunger in which it is placed. The yoke B is recessed also from front to rear, as shown in Fig. 2 in full lines b b, and in dotted lines c c in Fig. 50 1. This recess receives the end of the lever C,

with or without its friction-wheel d. The wheel d is pivoted between two prongs, e e, of the lever C, and bears against the inner surface of the block above and below, being fitted accurately thereto. The pronged end of the lever, 55 as shown in dotted lines in Fig. 1, is reduced in depth, so as to be less than the vertical measurement of the recess in the yoke, in order to prevent the lever from binding against the top and bottom of the recess in its move- 60 ment.

Fixed to the sliding yoke B are two rods, f g. The rod f is fixed in the upper end of the yoke, and extends through a sleeve, h, in the upper cross-bar of the plunger, through which 65 it slides freely. It is threaded, and is provided with nuts i i, which, when turned to bear against the ends of the sleeve h, hold the yoke B in any required position within the plunger, or the position of the yoke may be shifted at pleasure, within the limits of the chamber of the plunger, by movement of the nuts i i. The rod g is fixed in the lower part of the yoke B and passes through a hole in the lower part of the plunger, serving simply as a guide for the yoke, 70 and may be dispensed with.

It will be understood that the plunger A may receive any suitable die, such as are ordinarily used on this class of machines, and whenever, for any reason, it be desired to raise the 80 plunger or to lower it, in order to increase or diminish the space between the lower limit of its motion and the lower die or bed-plate, it can be readily accomplished by turning the nuts i i.

In machines of this class, in which the lever directly operating the plunger is moved by a treadle-lever, such as that shown at D, it is necessary to have an adjustable stop with a leather or rubber bumper for the treadle-lever, 90 and adjustable connection between such treadle-lever and the lever directly operating the plunger, in order that the movement of the upper die may be accurately determined. We have provided special devices for this purpose, 95 as shown in Fig. 1. The adjustable stop consists of a piece, E, formed substantially of T shape, as shown in the figure. It is attached to the lever by means of the pivotal bolt which passes through its longer arm l, while the up- 100

per arm, *k*, rests against the flange of the leg. A horizontal arm, *m*, extends directly over the treadle-lever *D*, and is provided with a rod, *n*, which passes freely through a vertical hole in the said horizontal arm. The rod *n* is threaded, and is held in any position by nuts *o o*, and is provided with a head, *p*, with a leather or rubber bumper, which bears directly against the treadle-lever and limits its upward movement. 10 Connection between the levers *C* and *D* is formed by a bar, *F G*, the two parts of which *F G* are provided with right and left hand screws *q r*, which work in nuts *s s* fixed upon a hollow sleeve, *t*. The sleeve *t* is provided 15 with a hand-wheel, *u*, and by turning this hand-wheel the connecting-bar *F G* may be readily lengthened or shortened.

We are aware that adjustable connecting-rods are commonly used for various purposes, 20 as well as adjustable stops, and upon these points we desire to have it understood that we limit our claims to the precise devices shown.

Having thus described our invention, what we claim is—

1. In a metal press, the combination of the 25 sliding head *A*, carrying a die, the operating-lever *C*, and the block *B*, adjustable within said sliding head *A*, substantially as described.

2. The combination, with a reciprocating slotted head, *A*, carrying a die, and with the 30 lever *C*, of the yoke *B*, having the screw-rod *f* and the adjusting-nuts *h i*, as described.

3. The adjustable stop *E*, in combination with the rod *n*, nuts *o o*, and treadle-lever *D*, substantially as described. 35

4. The combination of the reciprocating head *A*, the adjustable yoke *B*, the operating-lever *C*, and the friction-roller *d*, as described.

In testimony whereof we have signed our names to this specification in the presence of 40 two subscribing witnesses.

WILLIAM H. H. STEVENSON.

JOHN SOLTER.
